UNITED STATES PATENT OFFICE

NILS A. WAHLBERG, OF WILKINSBURG, PENNSYLVANIA, ASSIGNOR TO WESTINGHOUSE ELECTRIC & MANUFACTURING COMPANY, A CORPORATION OF PENNSYLVANIA

TRANSMISSION-LINE DEVICE

Application filed November 2, 1927. Serial No. 230,459.

My invention relates to transmission-line devices and particularly to electrostatic-field-control structures for high-voltage insulators.

One object of my invention is to provide a device of the above-indicated character that shall be adjustable to adapt it to different structural and electrostatic conditions in the service for which it is intended.

Another object of my invention is to provide an electrostatic field-control shield that shall be protected against damage by movement of a transmission-line conductor in certain service in which it may be employed.

Another object of my invention is to provide a disc-like electrostatic-field-control shield which may be mounted centrally relative to an insulator, while the latter is in operative position relative to a conductor and a supporting tower.

A further object of my invention is to provide a transmission-line device that shall be simple and durable in construction, economical to manufacture and effective in its operation.

In high-voltage transmission-line practice, it has been usual to provide arcing horns or rings and electrostatic-field-control shields at one or both ends of the insulators which support the conductors. These devices have, however, to the best of my knowledge, all been of fixed shapes and sizes and each only adapted for one particular service or set of conditions.

Also, while arcing rings have been suggested that may be placed in position around the insulator axis while the insulator is in operative position between a tower and a conductor without detaching it, it is not known to me that a disk-like shield has ever been so adapted.

Further, in certain service recently developed wherein a clamp normally holds a conductor securely but permits the conductor to slip therethrough under certain abnormal conditions, while it has been suggested to provide a removable section of an arcing ring to prevent damage thereto by contact with the line conductor, it is not known to me that a disk-like electrostatic-field-control shield,

which is a quite different structure from a ring, has been so adapted.

It is my aim, therefore, to provide a structure that includes one or all of the features above mentioned as not having been employed before, whereby an electrostatic-field-control device shall be provided that may be adjusted to various conditions and that may be in the form of a disk-like shield for mounting about an insulator axis, while the insulator is in service, and that has a removable section to prevent damage thereto by contact with the conductor.

Accordingly, in practicing my invention, I provide a field-control structure having relatively adjustable movable parts to vary the field-controlling character and that, where employed as a disk-like shield, is so constructed as to permit its mounting relative to an insulator, in the operative position of the latter, and to prevent damage to the disk by engagement with the conductor.

Figure 1 of the accompanying drawing is a top plan view of a transmission-line device embodying my invention.

Fig. 2 is a partially sectional side view, taken along the line II—II of Fig. 1, an insulator being shown that is not shown in Fig. 1, and

Fig. 3 is a sectional view taken substantially along the line III—III of Fig. 2.

The structure illustrated comprises, in general, an insulator 2, a suspension clamp 3 for the reception of a transmission-line conductor or cable 4 and an electrostatic-field-control device 5 of my invention.

The insulator 2 is one of a usual series-string suspension type for connection, at its upper end, to a pole, tower or other main support (not shown) and needs no further description, so far as my invention is concerned, except that it may swing, from left to right, from its normal position shown, about its point of suspension on the tower.

The clamp 3 may be of any usual type but, as shown, is of a type set forth in my co-pending application, Serial No. 209,441, filed July 30, 1927, and not specifically pertinent to my present invention beyond the fact that,

when the insulator swings a certain distance to the left or to the right, as above mentioned, it permits the conductor 4 to slip therethrough. It effects this function through the co-operation of a main conductor-receiving channel member 7 having upper extensions 8 between which a cam 9 is pivotally mounted, an upper clamping shoe 10 that is held in position by a leaf spring 12 and the cam 9, a yoke 14 that is pivotally mounted on trunnions 15 held in line with each other opposite the conductor 4, by links 17 and a bolt 18, and a central projection 19 on the yoke that cooperates with the cam 9 to release the latter, when the channel member 3 and the yoke 14 are moved angularly relative to each other about the trunnions 15.

The electrostatic-field-control device 5 comprises substantially parallel elongated supporting members 21 of L-shape in cross-section having vertical side legs 22 secured to lugs 23 on the yoke 14, by screws 24, and oppositely-projecting horizontal upper legs 25.

Half-shield members 27 and 28, which together constitute a general structure of disk-like character having widely rounded or tube-like outer perimetral edges 29 and upturned perimetral portions or ends 30, are preferably constructed of relatively thin sheet metal having overlapping telescopically related adjacent or intermediate portions 32 and 33, respectively.

The portion 33, which is above the portion 32, is provided with elongated slots 35, extending parallel to the conductor 4, through which screws 36 extend into the arms 25 of the supporting members 21, a central inner portion being cut-away to permit the portion 33 to enclose three sides of the yoke 14.

Similarly, the portion 32, which is fitted under, or into the inner portion of, the half portion 33, is provided with slots 38 through which screws 39 extend into the arms 25 of the supporting members 21, a portion being cut-away so that it encloses three sides of the yoke 14, including a side which is not embraced by the portion 33.

In operation, the structure, as above described, permits the halves 27 and 28 of the field-control structure 5 to be telescopically fitted to each other about the axis of the insulator 2, while the latter is mounted in operative position between the tower and the clamp 3, without detaching the insulator from either the tower or the clamp, as where a one-piece shield or other annular member is employed.

By manipulation of the screws 36 and 39, and by moving the halves 27 and 28 along a diameter substantially parallel to, and above, the conductor 4, the area of the shield presented to the field above the clamp may be varied, within certain limits, and fixed in adjusted position. This feature and the

upturned ends 30 are to adapt the shield to different conditions of service and to compensate for the effects of the conductor 4 and of other parts, which may vary in character, on the electrostatic field of the insulator. 70

The half portions 27 and 28 of the shield 5 may be provided, at the ends thereof, with sections 40 and 41 which are pivotally mounted, as by hinges 43 and 44, respectively, to the main bodies of the halves 27 and 28, and which normally lie flush with the adjacent surfaces of the shield. When, by reason of breaking of the conductor 4 between its main supports, the structure illustrated swings a certain distance to the right or to the left, as viewed in the drawing, about its tower support at the upper end of the structure, the channel member 3 and the yoke 14 move angularly relative to each other. This movement causes the projection 19 on the yoke 14 to actuate the cam 9 to release the conductor. 80 85

Also, during the above-movement, the conductor 4 and the shield 5 tend to come together violently at one end of the shield, which might ordinarily damage the shield and render it unfit for further service. However, in my structure, such damage is prevented by reason of the fact that the sections 40 and 41 move with the conductor and are automatically restored to normal position when normal line conditions are restored. 90 95

By my invention, a structure is provided that is of ready and economical manufacture, is easy to install, adapts itself to insulators, clamps and main supports of various types and sizes, has the other advantages above mentioned, and is, in general, an improvement in the art to which it relates. 100 105

While I have shown and described a particular form of my invention, changes may be effected therein without departing from the spirit and scope thereof, as set forth in the appended claims. 110

I claim as my invention:

1. In a transmission-line device, the combination with an insulator, of an electrostatic-field-control structure including a portion for mounting the structure relative to the insulator and an extensible field-control element surrounding the insulator axis on said portion. 115

2. In a transmission-line device, the combination with an insulator, of an electrostatic-field-control structure including a portion for mounting the structure relative to the insulator and a field-control element adjustably mounted on said portion for varying the field-controlling operation of the structure and having a section relatively movable in response to certain movements of the line. 120 125

3. In a transmission-line device, the combination with an insulator, of an electro- 130

static-field-control shield structure therefor including a portion for mounting the shield relative to the insulator and half-shield portions mounted thereon for relatively movable adjustment along a diameter of the shield.

4. In a transmission-line device, the combination with an insulator, of an electrostatic-field-control shield structure therefor including a portion for mounting the shield relative to the insulator and half-shield portions mounted thereon for relatively movable adjustment along a diameter of the shield, said half-portions having substantially telescopically related tube-like perimetral edges.

5. In a transmission-line device, the combination with an insulator, of an electrostatic-field-control shield structure therefor including a portion for mounting the shield relative to the insulator and half-shield portions mounted thereon for relatively movable adjustment along a diameter of the shield, said half-portions having registering slots, and means in said slots cooperating with said mounting portion.

6. In a transmission-line device, the combination with an insulator, of an electrostatic-field-control shield of substantially disk-like character including a section relatively movable to the remainder thereof in response to certain movements of the line.

7. In a transmission-line device, the combination with an insulator disposed between a line conductor and a main supporting structure, of a disk-like electrostatic-field-control shield mounted normal to the axis of the insulator and including portions whereby the shield may be mounted and dismounted relative to the insulator while the latter is in operative position relative to said conductor and said structure.

8. In a transmission-line device, the combination with an insulator, of an electrostatic-field-control structure including a portion for mounting the structure relative to the insulator and an extensible field-control disk-like shield disposed centrally, and extending laterally, relative to the insulator.

9. In a transmission-line device, the combination with an insulator, of an electrostatic-field-control structure therefor including a portion for mounting the structure relative to the insulator and a disk-like shield element having relatively adjustable portions for varying the field-control surface of the shield.

In testimony whereof, I have hereunto subscribed my name this 26th day of October, 1927.

NILS A. WAHLBERG.
